UNITED STATES PATENT OFFICE.

T. MELLON ROGERS, OF PHILADELPHIA, PENNSYLVANIA.

ORE-SEPARATOR.

SPECIFICATION forming part of Letters Patent No. 236,180, dated January 4, 1881.

Application filed May 31, 1880. (No model.)

To all whom it may concern:

Be it known that I, T. MELLON ROGERS, of the city and county of Philadelphia, and State of Pennsylvania, have invented a new and useful Jigging-Machine for Separating Ores, of which the following is a specification.

The object of my invention is an improvement in jiggers for the separation of ores from their impurities, &c., based on the difference 10 of their specific gravities. In connection with the tank employed, I use a perforated, grated, of sieve-bottom box and an agitating-gate, by which water is forced through the perforations of the box, and thus separates the heavier 15 and lighter parts.

Figure 1 is a side perspective elevation, in which part of the framing is removed for the purpose of making the application of the improvement more obvious. Fig. 2 is a plan 20 view. Fig. 3 is a side elevation, sectioned, of the agitating-gate apart from the jig, to show more clearly the nature and construction of the same. Fig. 4 is a sectioned elevation of an eccentric for changing the throw of 25 the agitator.

Similar letters refer to similar parts throughout the several views.

A is the tank or box of the jigger, which is divided by the partition B into the agitating 30 and refuse chambers C D. A water-reservoir, E, is formed from the latter by a swinging partition and agitator, F, which moves watertight against the edges and curved bottom of the partition B. This agitator has one or more 35 valves, G, for admitting to the tank or chamber C the water which is supplied by the pipe H.

I is a screen, perforated or sieve-bottom box, and ore-holder at the top of the chamber C. In this instance it is shown in connection with 40 leveling adjusting-screws J, though it may be either fixed or movable.

In front of the tank is a bed or frame-work, K, across which is placed a shaft, L, having upon it an eccentric, M, and a pulley or gear 45 wheel, N, in line with a similar pulley or wheel, O, on a parallel shaft, P, which has the fast and loose pulleys Q Q' on its other end, so that the transmitting-belt R may be shifted at pleasure from one pulley to the other, and thereby 50 put the shafts L P in or out of motion. A rod, S, of the eccentric M passes into the tank and connects with the agitating-gate F.

Lumps of ore too large to pass the grated bottom are placed in the box I, and other pieces small enough to drop through the 55 meshes are filled in to a suitable depth. After water has been turned on the pipe H and power applied to the pulley Q, the movement of rotation which is produced in the shaft P is communicated, by the pulley or gear N, to the 60 eccentric M, which operates the rod S and imparts a reciprocating motion to the gate or agitator F, every vibration of which agitates and lifts the water of the chamber C through the sieve-bottom box I and gives a shaking 65 motion to the ore, by which its gangues, sands, and impurities are washed over into the chamber D, to be drawn off through a spout, T. During the agitation the smaller and heavier 70 particles of the ore drop through the meshes of the grate or sieve a into the chamber C, from which they can be washed out through the bottom opening U.

The supply of water in the chamber C is kept up by the valves G in the gate F, the 75 movement of which in the direction of the ore-box I increases the water-space of the chamber E, and pressing, during its return motion, against the augmented bulk of water, forces the valves G open and drives the water into 80 the chamber C. The return vibration permits the springs b to close the valves firmly against their seats.

The degree of water agitation in the chamber C for washing the ore contained in the box 85 I is regulated by the extent of vibration of the gate F. To that end, therefore, the throw of the eccentric M is made adjustable, in this instance, as follows: Slots c are formed in it, through which pass the shaft L and the holding-bolts d, for attaching to a collar or swell, e, of the same shaft. When the bolts are loosened the center of the eccentric can be adjusted to or from the center of the shaft, and the throw changed in proportion to the degree of 90 agitation required to be effected by the gate. I do not confine myself to this eccentric as shown and described, but claim, broadly, an adjustable eccentric.

I claim as my invention and desire to secure 100 by Letters Patent—

1. In an ore-jigger, the combination, with the gate F, provided with valves G and adjustable device for vibrating said gate and varying

the extent of its vibrations, of the vertically-adjustable ore-box having a grated or perforated bottom, whereby the force of the water and the continuance of its contact with the ore 5 may be regulated, essentially as set forth.

2. The box A, having the curved partition B, in combination with the vertically-adjustable ore-box having a grated or perforated bottom, and the gate F, having valves G and ad-

justable device for vibrating the same, substantially as described.

In testimony whereof I hereunto sign my name in presence of two subscribing witnesses.

T. MELLON ROGERS.
